A. C. WHIDDEN

VARIABLE FLUID SUPPLYING DEVICE

Filed Sept. 24, 1923

James P. Townsend
his atty

UNITED STATES PATENT OFFICE.

AUSTIN C. WHIDDEN, OF LOS ANGELES, CALIFORNIA.

VARIABLE-FLUID-SUPPLYING DEVICE.

Application filed September 24, 1923. Serial No. 664,485.

To all whom it may concern:

Be it known that I, AUSTIN C. WHIDDEN, a citizen of the United States, residing at Los Angeles, in the county of Los Angeles and State of California, have invented a new and useful Variable-Fluid-Supplying Device, of which the following is a specification.

This invention relates to means for delivering from different sources various characters of liquid ranging from a pure liquid delivered from only one of the sources through all degrees of mixture with liquid from another source, to a pure liquid delivered from the other source only, and the device is particularly designed for drawing from hot and cold water sources a stream of water having any desired temperature between and including that of each of said sources.

An object of the invention is to provide simple and effective means for opening and closing the hot and cold water valves singly or simultaneously as desired, and to so construct the operating means that it will actuate both valves alike or disproportionately as desired.

The invention is broadly new, basic and pioneer in that the positions of the hot and cold water valves are determined by the operation and the position of a wedging block that can be moved to operate the hot and cold water valves equally or unequally to open both in proportional relation, or either of them independently of the other.

An object of the invention is to provide simple means for mixing and delivering hot and cold water at a predetermined temperature.

An object is to provide an appliance of the character stated, that is especially adapted for use with wash bowls and tubs and which in connection therewith will be mainly hidden from in front; only a hand lever and discharge spout being exposed above and at the rear of the bowl or tub, and these parts being adapted to ornamental and porcelain or plated finish.

An object of the invention is to provide an appliance of the class referred to that is cheap, simple and durable in construction; and easy to assemble, install and operate.

Features of the invention are shown in the construction, combination and arrange-

ment of the parts to secure ease for adjustment and operation of the lever block.

Other objects, advantages and features of invention may appear from the accompanying drawing, the subjoined detail description and the appended claims.

The accompanying drawing illustrates the invention.

Fig. 1 is a front perspective view of a wall wash bowl provided with a water control appliance constructed in accordance with this invention.

Fig. 2 is an enlarged fragmental section on line x^2 , Fig. 1.

Fig. 3 is an enlarged fragmental section on line x^3 , Fig. 2.

Fig. 4 is a fragmental section on lines x^4 , Figs. 2 and 3.

Fig. 5 is an enlarged plan view of the adjustable block for the hand lever.

Fig. 6 is a side view of the adjustable block on a slightly smaller scale.

Fig. 7 is a front view of the block.

Fig. 8 is a section through the block on line x^5 , Figs. 5 and 6.

Fig. 9 is a section on line x^6 , Figs. 5 and 6.

Fig. 10 is a cross section on line x^{10} , Fig. 7.

Fig. 11 is a cross section on line x^{11} , Fig. 7.

Fig. 12 is a cross section on line x^{12} , Fig. 7.

Fig. 13 is a fragmental section on line x^{13} , Figs. 2, 4 and 5 omitting the guide rods.

The water or fluid control appliance 1 is shown operatively connected to a wash bowl 2 which can be of any desired construction; but is preferably provided with an apron 3 that extends rearwardly and upwardly and is connected to a wall 4 in any well known way as by means of the bolts 5, see Fig. 2.

A forked bracket 6 is secured to the rear of the bowl 2 as by bolts 7 and has a rocker bearing 8 pivoted between the forks on a bolt pin 9; and provided with a socket 10 in which the lower end 11 of an intermediately threaded hand lever 12 is journaled, supporting on its threads 13 an adjustable reversely thickened oscillating valve-operating wedging block or member 14 threaded thereon and having an intermediate thin part as at c, d, e, f. The upper portion of the lever 12 extends through a

guide slot 15 in the apron 3 and has a handle 16 secured thereto. Preferably the threaded portion 13 is constructed with a quick thread as best illustrated in Fig. 13.

5 The rocker bearing 8 has side lugs 17 to which upright guide rods 18 are secured as by nuts 19, 20.

The rods 18 extend upward through openings 21 in the block 14 to a position slightly higher than a boss 22 on the lever 12, and also through a plate 23 that is seated on the boss 22; and the upper ends of the rods 18 are secured to the plate 23 by nuts 24, 25 by which means the lever 12 is securely but loosely mounted in the rock bearing 8 so that it can be rotated to drive the block 14 upward or downward on the screw 13 and rods 18; and also, so that it can be pivotally moved on pin 9 and actuated forward or backward in the slot 15 to move the block 14 in the arc of a circle to open the hot and cold water valves 26, 27 or to permit them to be closed by the springs 28, 29 that normally hold the valves closed.

25 Said valves 26, 27 respectively control the hot and cold water passage 26', 27' to the common passage or outlet as at 41.

30 Springs 28, 29 are arranged between the stationary abutments 30 that are integral with the valve casings 31, 32 and the bosses 33 on the valve stems 34, 34'.

The outer ends of these stems are provided with anti-friction bearings 35, 35' that are shown as balls actuated by the side walls of the block 14.

40 Hot and cold water pipes 36, 37 are connected with the respective valve casings 31, 32 through which the water passes when the valves are open to pipes 38, 39 that are connected to a common pipe 40 that forms a mixing chamber and terminates in the discharge nozzle 41 over the bowl 2.

The foregoing construction of the hot and cold water valve is for the purpose 45 of illustration, it being understood that I may employ any standard valve and pipe connection adaptable to the construction, arrangement and assembly of my appliance.

50 Block 14 can be adjusted and actuated to open either of the valves 26, 27 separately, or both together in various proportions; that is, both valves can be opened equally or one more than the other.

55 The block 14 is provided with inclined surfaces *a*, *a'* that are arranged to open the valves 26, 27 separately when the block is moved up or down on the guides 18 by the screw 13. When the block is moved 60 downward the inclined surface *a* actuates the ball 35, stem 34, to open valve 26. During this downward movement of the block, the valve 27 is permitted to remain closed by reason of the construction and arrangement of the surface *b* that is opposite to

the surface *a*; that is to say, the surface *b* is parallel to the guides 18 so that in the downward movement of the block described, the ball 35' is not actuated outward from the mid line of the block; unless the block 70 is moved forward in an arc as well as downward; in which latter event both valves will open.

The reverse or upward movement of the block on the screw 13 and guides 18 will 75 reverse the operation of the valves. When the block is moved upward the surface *a'* will engage the ball 35' and through the stem 34' open the valve 27, and the surface *b'* which is substantially the counter part of *b* in reverse position, will not actuate the valve 26 unless forward movement is given to the block; in which latter event both valves will open.

80 The valves 26, 27 are normally closed when the block 14 is in a position in which the balls 35, 36' are at its front edge 44 and at mid-center thereof; or with the balls engaging neutral places on the surfaces *b*, *b'* in either of which positions a forward arc movement of the block will cause both valves to open an equal amount.

85 The block 14 has a rectangular rear surface 45 and rear side portions 46, 47 that are rectangular; the rectangular portion of side 46 is shown in Fig. 6 as enclosed by the lines *x-y*, *y-o*, *o-m* and *m-x*; and the other side 47 is provided with a similar rectangular surface; and forward of these 90 spaces are arranged the surfaces for actuating the valves 26 and 27. These surfaces *a*, *a'* and *b*, *b'* are arranged on opposite sides of the block and in staggered relation to one another; that is, the face *a* is opposite to the face *b* and the face *a'* opposite the face *b'*; and these faces or planes are arranged so that the face *a* intersects the face *b'* at the line *c*, *d* and the face *a'* intersects the face *b* at the line *e*, *f*.

100 Referring particularly to Fig. 6, the face *a* begins at the top of the block 14 on a line *m*, *n*, that extends perpendicular to planes across the front 44 and back 45 of the block; and from the line *m*, *n*, the face *a* extends 105 downward toward the line *c*, *d*, in a plane in which the forward line, *n*, *d* is inclined inwardly toward the center of the block and the line *m*, *c*, extending perpendicular to line *m*, *n* and parallel to the back edge line *x-y* of the block; and terminates at 110 the line *c*, *d*.

115 The face *b'* begins on the line *o*, *p* that is inclined from the point *O* inward toward the center of the block; and it extends upward in a plane with the lines *n*, *d* and *o*, *c* thereof parallel to the back edge line *x-y* of the block; and terminates in the line *c*, *d*; and the construction and arrangement 120 of the surfaces *a'*, *b* are substantially like that of the surfaces *a*, *b'*, except that they 125

130

are on the side 47 of the block and their position reversed.

In practice the parts are assembled as described; and the valves closed; in which 5 position the balls 35, 35' are arranged at the forward edge 44 and mid-center of the block, and the operating lever is in a vertical position or adjacent the back of the slot 15. In this position the valves 26, 27 close 10 the passages.

If the operator desires to obtain hot and cold water in equal proportion, the lever 12 is moved forward in the slot 15 which causes the block to move forward in an arc 15 and also causes the equally inclined surfaces *b*, *b'* through the connection described 20 to open the valves 26, 27 equally.

Assuming that only hot water is desired 25 and that valve 26 is the one to be actuated, the lever 12 is turned on its axis to drive the block downward until the surface *a* opens the valve 26; and during this movement the cold water valve remains closed. Then assuming that with the hot water valve 26 is 30 opened by surface *a* and that the operator desires to reduce the temperature of the water, the lever is drawn forward, thus causing the outwardly inclined surface *b* to open the cold water valve in any degree 35 until it equals the opening of the hot water valve. In other words the forward movement of the block 14 in an arc eventually moves both balls 35, 35' to the rectangular side surfaces 46, 47 that are equally distant 40 from the center of the block, so that both valves are opened equally.

When only cold water is desired, or a reduction of temperature is to be accomplished, the reverse movement of the parts 45 is in order.

By the foregoing construction, combination and arrangements of the parts of my appliance, the hot and cold water valves can be opened separately at any point up to 50 and including full flow and actuated together to open equally or unequally in various proportions.

I claim:

1. The fluid controlling appliance set 55 forth comprising valves adapted to discharge through a single outlet; a reversely thickened wedging block having an intermediate thin portion interposed between and connected to operate said valves; and a lever for actuating said block to open and close said valves.

2. The fluid controlling appliance set 60 forth comprising valves; stems to said valves; a reversely thickened wedging block having an intermediate thin part interposed between said stems; and a threaded lever for moving the blocks to actuate the block to open and close the valves.

3. The fluid controlling appliance set 65 forth comprising valves adapted to normal-

ly close passages; stems to said valves; a wedging block having inclined faces interposed between the free ends of, and arranged to separate said stems; and a pivotally mounted threaded lever for actuating said 70 block up and down and forward and back to open said valves.

4. The appliance set forth comprising valves adapted to normally close passages; stems to said valves; said stems extending 75 from said valves toward and adjacent to one another; anti-friction bearings on the adjacent ends of said stems; a wedging block arranged between and adapted to operate on said bearings; a lever having a threaded portion extending through said block; guides for said block; and a rocking bearing on which said lever is rotatably mounted, said block adapted to be moved on and by said lever to open said valves. 80

5. The fluid controlling appliance set forth comprising valves adapted to normally close passages to a common outlet; stems to said valve; said stems extending 85 from said valves toward and arranged with their free ends adjacent one another and in axial alignment; ball bearings on the free ends of said stems; a wedging block arranged between said bearings; and means for moving said block in an arc to open 90 said valves.

6. The fluid controlling appliance set forth comprising valves adapted to normally close passages to a common passage; axially aligned stems to said valves; said stems extending from said valves toward each other and arranged with their free ends adjacent each other; ball bearings on the free ends of said stems; a wedging block arranged between said bearings and adapted 100 to be adjusted upward or downward to open said valves separately; and means for moving said block in an arc to open both of 105 said valves.

7. The water controlling appliance for 110 receptacles set forth comprising a bowl; a bracket on said bowl; a rocking bearing pivoted on the free end of the bracket; a lever having one end rotatably mounted in said bearing; a block adjustable on said lever, 115 said block being movable in an arc; and valves adjacent said block that are adapted to be opened by movement of said block according to adjustment on said lever or movement in an arc.

8. The water controlling appliance for 120 receptacles set forth comprising a bowl having an apron with a slot therethrough; a bracket attached to said bowl; a rocking bearing pivotally connected to said bracket; a lever rotatably mounted in said bearing; 125 said lever extending upward through the slot in the apron of said bowl and normally arranged in a vertical position; a wedging block movable upward and downward on 130

- said lever by rotation of said lever; a valve adjacent said block and adapted and arranged to be opened when said block is moved upward; and a valve adapted and arranged to be opened when said block is moved downward; said block and lever being arranged so that said block can be moved in an arc to open both valves together.
10. A fluid controlling device comprising passages leading to a common passage; valves for the passages respectively; a wedging block having various wedging faces to actuate said valves; and means adapted to move the block in one direction to cause valve operation and in another direction to cause a different valve operation.
10. The fluid controlling appliance set forth comprising valves adapted to normally close passages; stems to said valves; a wedging block having inclined faces interposed between the free ends of said stems; and means to move said block up and down and forward and back to open and close said valves.
11. A fluid controlling device comprising passages; valves for said passages respectively; a wedging block having various wedging faces to operate said valves; and means adapted to move the block in one direction to cause operation of one of said valves, and in another direction to cause operation of another of said valves, and in a third direction to cause simultaneous operation of both of said valves.
12. A fluid controlling appliance comprising passages to conduct liquids of different characters, valves to control said pas-
